UNITED STATES PATENT OFFICE.

HENRY LITTLETON, OF MARICOPA, CALIFORNIA.

BURNER.

1,031,278.

Specification of Letters Patent.

Patented July 2, 1912.

Application filed November 2, 1911. Serial No. 658,183.

To all whom it may concern:

Be it known that I, HENRY LITTLETON, a citizen of the United States, residing at Maricopa, in the county of Kern, State of California, have invented certain new and useful Improvements in Burners; and I do hereby declare the following to be a full, clear, and exact description of the invention, such as will enable others skilled in the art 10 to which it appertains to make and use the same.

This invention relates to that class of oil burners described in my co-pending application for Letters Patent filed Aug. 17, 1911, 15 under Serial Number 644,517.

An objection to this type of burner in which a single jet of steam is relied upon to atomize the oil, is that the jet usually atomizes only the lightest portions of the hydrocarbons and forces the heavier portions but slightly in advance of the nozzle, and as a result these heavier portions drip down through the grate bars and are not fully utilized. To obviate this disadvantage, I 20 provide in the present invention an auxiliary steam supply which serves to raise the temperature of the cooled partially atomized fuel so that substantially complete atomization takes place before entrance of the fuel 25 to the furnace.

With the above object in view the invention consists of the certain novel details of construction and combination of parts hereinafter fully described and claimed, it being 30 understood that various modifications may be made in the minor details of construction within the scope of the appended claims.

In the accompanying drawing forming part of this specification:—Figure 1 is a side 40 elevation of a burner embodying my improvements. Fig. 2 is a longitudinal sectional view through the burner. Fig. 3 is a cross sectional view taken on the line 3—3 Fig. 2.

45 Referring now to the drawing in which like characters of reference designate similar parts, 10 designates the oil supply T coupling, one of the alined branches of which is closed by a reducer 11, the same being internally threaded for the reception of the threaded end of a steam jet pipe 12 which extends axially through the alined branches of the coupling and projects beyond both ends of the branches. One end of the jet pipe is equipped with an elbow connection 13 which may be connected in any preferred

manner to a steam supply. The lateral branch 10' of the coupling is connected in any suitable manner to an oil supply. An outlet elbow 10'' is connected to the coupling 60 for drawing off the contents thereof when desired.

A reducer 14 is threaded into the other of said alined branches and a T-coupling 15 is threadded on to this reducer, the reducer 65 being furthermore provided with a threaded axial nipple 16 for the reception of the threaded end of an oil pipe 17 which houses the steam jet pipe 12 and extends axially through the alined branches of the T-coupling 15. The oil pipe extends slightly beyond the discharge end of the steam jet pipe so that the oil is mixed with steam before its escape from the oil pipe. During 70 such mixing it is evident that the temperature of the fuel will be lowered so that complete atomization does not take place. To raise the temperature of this atomized fuel I connect the lateral branch of the coupling 15 with suitable steam supply, suitable 75 pipe connections as will be presently described being employed to conduct this supply of steam to the fuel escaping from the oil pipe.

Threaded into the T-coupling 15 is a nipple 18 which houses the oil pipe, and is furthermore equipped with a pipe extension 19, the reducer connection 19' between both 80 of these parts being disposed at the discharge end of the oil pipe so that the extension may be unscrewed to permit access to the discharge end of the oil pipe for cleaning and repairs. The outer end of the extension is preferably equipped with an elbow 20 which is provided in its front wall 85 with a discharge slot 21 and is furthermore provided below the slot with a small supplementary discharge orifice 22 as described in the above mentioned co-pending application, this elbow co-operating with the extension 19 in forming a mixing chamber.

By now referring to Fig. 2 it will be seen that the independent supply of steam led into the T-coupling 15, is conducted through the nipple 18 and reducer connection 19' to the discharge end of the oil pipe where by virtue of its higher temperature than the cooled atomized fuel, it merges with and raises the temperature of the fuel so that substantially complete atomization takes 105 place before escape of the fuel through the discharge openings into the furnace.

In order that the jet pipe 12 may be held centered within the oil pipe 17, a plurality of screws or the like 23 are inserted radially through the oil pipe and advanced 5 into engagement with the jet pipe.

What is claimed, is:—

A burner including a T coupling having the lateral branch adapted for connection to an oil supply, longitudinally bored plugs 10 closing the alined branches of said coupling and one of said plugs having an exteriorly threaded nipple projecting beyond said coupling, a steam jet pipe in said coupling threaded into the bore of one plug and extending 15 through the bore of the other plug, an oil conducting pipe threaded into the bore of the last named plug surrounding said jet pipe and extending beyond the

discharge end thereof, a second T-coupling having one of the alined branches threaded on to said nipple and having the lateral branch adapted for connection to a steam supply, a pipe threaded into the other alined branch of said coupling surrounding said oil supply pipe and terminating short of 20 the discharge end thereof, a reducer threaded on to the discharge end of the last named pipe, and a pipe threaded into said reducer and alining with said oil supply pipe. 25

In testimony whereof, I affix my signature, in presence of two witnesses.

HENRY LITTLETON.
